CLAIM

The ornamental design for a fuel tank as shown and described.

DESCRIPTION

FIG. 1 is a top, front and right side perspective view of a fuel tank embodying our new design;

FIG. 2 is a bottom, rear and left side perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged and partial perspective view of detail 9 in FIG. 1;

FIG. 10 is an enlarged and partial perspective view of detail 10 in FIG. 1;

FIG. 11 is an enlarged and partial perspective view of detail 11 in FIG. 1;

FIG. 12 is an enlarged and partial front elevation view of detail 12 in FIG. 3;

FIG. 13 is an enlarged and partial rear elevation view of detail 13 in FIG. 4;

FIG. 14 is an enlarged and partial left side elevation view of detail 14 in FIG. 5; and,

FIG. 15 is an enlarged and partial top plan view of detail 15 in FIG. 7.

The dashed broken lines in the figures are for the purposes of illustrating portions of the fuel tank and form no part of the claimed design.

The short-short-long dashed broken lines immediately adjacent to the claimed areas in the views represent the boundaries of the design and form no part of the claimed design. The dash-dot-dash broken lines in the drawings do not represent structures and are provided for annotative purposes only to note the areas of enlargement.
